DESIGN FOR A CLOTHESPIN

Wesley L. Scharf, Inkster, Mich.

Application March 6, 1945, Serial No. 118,288

Term of patent 14 years

(Cl. D17—6)

To all whom it may concern:

Be it known that I, Wesley L. Scharf, a citizen of the United States, residing at Inkster, in the county of Wayne and State of Michigan, have invented a new, original, and ornamental Design for a Clothespin, of which the following is a specification, reference being had to the accompanying drawing, forming a part thereof.

I claim:

The ornamental design for a clothespin, as shown.

WESLEY L. SCHARF.
